UNITED STATES PATENT OFFICE.

JOHN C. GUNN, OF MARVIN, MISSOURI.

FORCE-FEED LUBRICATOR.

1,159,664.

Specification of Letters Patent.

Patented Nov. 9, 1915.

Application filed September 1, 1914. Serial No. 859,655.

To all whom it may concern:

Be it known that I, JOHN C. GUNN, a citizen of the United States, residing at Marvin, in the county of Morgan and State of Missouri, have invented certain new and useful Improvements in Force-Feed Lubricators; and I do hereby declare the following to be a full, clear, and exact description of the invention, such as will enable others skilled in the art to which it appertains to make and use the same.

My invention relates to force feed lubricators, and particularly to that class having automatic action.

My object is to supply an oiler, that will supply a positive and regular flow of lubricant at all times, and requiring but little attention.

In the drawing herewith illustrating my invention and which is made a part of this application, I have shown a side elevation with a vertical sectional view of the oil container and the ducts leading therefrom.

A frame 1 supporting the lubricator and the operating mechanism of the forced feed, is mounted upon the duct 2, said duct leading to the part to be lubricated.

The oil container comprises an inverted cup 4 and a member 3 serving as a closure for the cup 4. The member 3 is screw threaded on the outside at the point of its greatest diameter. The cup 4 is screw threaded throughout its length upon the inner side thereof, the threads on the member 3 engage the thread in the cup 4, whereby the said cup is caused to move downwardly upon the member 3 as the cup 4 is rotated. For convenience of removing member 3 from the frame so that the cup 4 may be more readily filled with oil, the lower end 5 of the member 3 is screw-threaded, these threads are cut in an opposite direction from the threads on the upper end of the member 3 so as to prevent it unscrewing when the cup 4 is turned on the member 3. Said member 3 has an aperture or duct extending throughout its entire length, to provide a passage for the oil from the cup 4 to the part to be lubricated.

Attached to the center of the top of the cup 4 is a stem 6 extending upwardly through the pinion 8. Said stem 6 is provided with a key seat 7 throughout its entire length. Positioned on this stem is a pinion 8 having a worm gear, the said pinion 8 is slidably mounted upon said stem 6 and to

prevent its turning on the said stem a loosely fitting key (not shown) is inserted in the key seat 7 but said key is securely fitted in the hub of said pinion 8. The said pinion 8 has an upwardly extending elongated hub 9 which extends through the upper cross bar of the frame 1 and is journaled therein. The said hub extends through the said frame a sufficient distance to permit a collar 10 to be mounted thereon, said collar is secured to said hub by means of a set-screw 11, where the said hub enters the frame, the diameter of the said hub is reduced to form a shoulder 12 thereon. This shoulder 12 and the collar 10 serves to hold the pinion 8 in its proper operative position and permits the stem 6 to be drawn through it by the action of the screw-threads on the member 3 and the cup 4. At the extreme upper end of the stem 6 a crank is secured to provide a means for quickly raising the cup 4 when it requires re-filling.

Connected to the lower end of the member 3 is a nipple 13 inserted in the frame which is screw-threaded to the duct 2, said nipple is provided with an aperture therethrough for the passage of oil from the member 3 to the duct 2. A counter shaft 14 is secured to the frame transversely to the stem 6, said counter shaft 14 being journaled in the boxings 15 and 16. Mounted on the central portion of the said counter shaft 14 is a worm-gear 15 securely keyed thereon. Said worm-gear being intended to engage the gear on the pinion 8 and to rotate the said pinion 8. The end of the counter shaft 14 extends beyond the boxing 16 and has, loosely mounted thereon an arm 17. Just beyond the bearing of the arm 17 the end of the counter shaft is reduced to form a shoulder. Upon the reduced part a ratchet wheel 19 having notches in its periphery is mounted and is secured to the counter shaft 14 by a nut 20 having a handle 21 attached thereto.

Pivotedly attached to the arm 17 adjacent the rim of the wheel 19 is a catch 22, mounted on the pivot 23, said catch being held in operative position by the counter weight 24, said counter weight being the enlarged lower end of the catch. The free end of the arm 17 is attached to a reciprocating part 25 of the machine on which the lubricator is located. The movement of this part is communicated to the arm 17, as the said arm moves backwardly and forwardly the catch engages the notches of the wheel 19 and moves it around

which turns the counter shaft 14, the shaft turns, through the worm gear 8 and 15, the stem 6 and the cup 4. Said cup through the action of the screw threads therein is moved 5 downwardly exerting a pressure on the oil in the cup 4 forcing a continuous feed of oil through the ducts in the member 3 and the nipple 13. If it is desired to stop the flow of oil, the nut 20 on the shaft 14 is loosened 10 which allows the wheel 19 to turn on the shaft 14 without turning the shaft.

From the foregoing description it will be seen that I have designed an automatic forced-feed oiler for using hard oil, one that 15 requires only to be kept filled to enable it to perform the function designed for it without further attention, and one adapted for use in inaccessible places on this account.

Believing that the construction, advantages and manner of using my invention have thus been made clearly apparent, further description is deemed unnecessary.

Having thus fully described my invention, what I desire to secure by Letters-Patent is:

1. A lubricator comprising a supporting frame; an inverted oil cup vertically movable within said frame and having screw-threads upon its inner surface; a fixedly

mounted closure for said cup having screw threads on its outer edge, and an aperture extending throughout its length; an upwardly extending stem attached to said cup and provided with a key way, and means slidably keyed to said stem to rotate said stem and said cup.

2. A lubricator comprising a supporting frame; an inverted oil cup having screw-threads upon its inner surface; a fixedly mounted closure for said cup, having screw threads on its outer edge, and an aperture extending throughout its length; an upwardly extending stem attached to said cup; a counter shaft attached to said frame; worm gears mounted on said stem and said counter-shaft; a swinging arm loosely mounted on said counter shaft, outside of said frame; a ratchet wheel detachably mounted on the end of said counter shaft, and a latch attached to said swinging arm and engaging the said ratchet wheel.

In testimony whereof I have signed my name to this specification in the presence of two subscribing witnesses.

JOHN C. GUNN.
